UNITED STATES PATENT OFFICE.

SIMEON S. JACKSON, OF HYDE PARK, MASSACHUSETTS, ASSIGNOR TO THE STAFFORD COMPANY, OF READVILLE, BOSTON, MASSACHUSETTS, A CORPORATION OF MASSACHUSETTS.

TRANSFERRER FOR WEFT-REPLENISHING LOOMS.

Application filed November 11, 1925. Serial No. 68,323.

The invention is designed for employment in looms of the class in which weft replenishment is effected through automatic insertion of a reserve bobbin or other weft-carrier or filling-carrier, loaded with weft or filling, into the working shuttle of a loom, with simultaneous ejection of the spent or failed carrier previously occupying the shuttle.

10 The invention has relation to the so-called transferrers, sometimes termed hammers, by which a fresh or reserve weft or filling-carrier is driven into a working shuttle, with resulting ejection of the spent or failed carrier. In practice, a transerrer or hammer is constructed with a head-portion which in operation strikes downward upon the top of the head of the carrier that is about to be placed in the shuttle, and in some cases it is 15 provided with a striker-block that is disposed at a short distance transversely from the said head-portion and arranged to act against the periphery of the wound mass of weft or filling upon the carrier to ensure 20 that the whole length of the carrier, including its tip-portion, shall become entered fully into the shuttle.

The invention provides in novel manner for mounting a striker-block in connection 25 with the arm of a transerrer or hammer, with facility for adjustment of the said striker-block laterally, so that it may be arranged to strike against the wound mass of weft or filling at the required place in the 30 length thereof, and also with capacity for angular adjustment.

Illustrative embodiments of the principles 35 of the invention are shown in the drawings. In the latter,—

40 Fig. 1 shows in side elevation a transerrer or hammer having an embodiment of the invention applied thereto.

Fig. 2 is an elevation of the rear end of 45 said transerrer or hammer, looking from the right-hand side in Fig. 1, a bobbin loaded with weft or filling, and a portion of a shuttle, being shown also.

Fig. 3 is a plan view of the parts which 50 are shown in Fig. 2.

Fig. 4 is a side elevation showing a modification.

Figs. 2 and 3 illustrate the head 1 and 55 striker-block 2 of a transerrer or hammer in the relations with respect to a bobbin 3

loaded with weft or filling 4 which they assume in the operation of driving such bobbin into the working shuttle 5 of a weft replenishing loom. As indicated in Fig. 1, the said head and striker-block are at the rear end of the transerrer-arm 6, the said arm extending rearward from the sleeve or hub 7 by means of which the transerrer or hammer is mounted upon a supporting-stud in a loom. The head 1 is furnished with a pin 8 projecting transversely outward therefrom, and striker-block 2 is mounted upon the said pin, the striker-block having a transverse hole 21 which is occupied by the said pin 8.

In accordance with the invention the hole 70 21 is intersected by a slit 22 in the material of the striker-block, and with those portions of the striker-block between which the slit intervenes, namely the side-portions or cheeks at opposite sides of the slit, I combine means for approaching the said side-portions or cheeks closer together in order 75 to contract the striker-block upon pin 8 so as to fit the latter tightly, and thereby hold the striker-block in the position upon the 80 said pin which has been given to the striker-block. In Figs. 1, 2, 3 the said means is constituted by a through-bolt 9 passing through holes in the said portions, or cheeks, with an enlarged head 91 at the exterior of one side-portion or cheek, and with 85 a nut 92 applied to the threaded stem of the said bolt at the exterior of the other side-portion or cheek.

In Figs. 1, 2, 3, the slit 22 extends from 90 the hole 21 to the top of the striker-block. In the modification shown in Fig. 4 the slit 221 extends downward diagonally from the hole 21 to one side of the striker-block, and the contracting means 95 is constituted by a screw 93 extending freely through a hole in the cheek 23 which is above the slit 221, with its head 931 against the outer side of said cheek, and its threaded stem screwed into a screw-100 threaded hole in the portion of the striker-block which is below the slit.

As will be apparent, loosening of the contracting means will render the striker-block free to be slid along the pin 8, either 105 toward or from the head 1, and also free to be rotated around the said pin, after which through tightening of the contracting means

the striker-block may be held fast in the position that has been given to it.

The described construction provides for mounting the striker-block upon the pin 8 of the transferrer or hammer, and for lateral and angular adjustment thereof, without requiring any holes, notches, or the like to be made in the said pin, and without any roughening or scoring of the pin as the result of fastening the striker-block in place thereon.

What is claimed as the invention is:—

1. The combination comprising a trans-
ferrer or hammer of a weft-replenishing
loom, a pin extending outward therefrom, a
striker-block having a transverse hole there-
10
15

through which is occupied by the said pin,
and split as described, and means for con-
tracting the wall of said hole upon the pin
to clamp the striker-block in adjusted posi-
tion upon the pin.

2. The combination comprising a trans-
ferrer or hammer of a weft-replenishing
loom, a pin extending outward therefrom, a
striker-block having a transverse hole there-
through which is occupied by the said pin,
and split as described, and a screw-threaded
member by which the portions at opposite
sides of the slit may be drawn together to
clamp the striker-block in adjusted position
upon the pin.

SIMEON S. JACKSON.
